SHORTS

Ernest G. Dann, New York, N. Y.

Application June 6, 1950, Serial No. 166,316

5 Claims. (Cl. 128—159)

1

This invention is primarily concerned with shorts or briefs for men. The improvement lies in an improved combination of materials that provides better support for the organs of a man and improved wearing qualities.

In continuous wear shorts are inclined to stretch because the knitted material of which they are made and the elastic bands around the legs and trunks are continuously under tension. When these shorts or briefs become stretched they hang loosely from the body and are unsatisfactory to the wearer in that they tend to slip off and do not provide the necessary support. The improvement here lies in an improved form of shorts, combining a woven material in a front fly-forming panel of the shorts and a knitted material in the rear panel. It has been found that a knitted garment having a front panel of woven goods is considerably more comfortable than the garment of all knitted material. The woven material gives a smoother and more uniform supporting and wearing surface. It feels more comfortable because of its more continuous surface and the supporting and load carrying action is better. In knitted goods all the support comes from the vertical wales which are non-elastic so that the supporting action is really that of a plurality of vertical tension lines. In woven goods this action is distributed uniformly in both directions and is therefore more comfortable.

An object of this invention is to produce an improved nether garment for men in the form of briefs or shorts combining a front panel of woven material and a rear panel of knitted material.

A still further object of this invention is to provide improved support for the organs of a man during the motion of the body but otherwise close conformity on the remainder of the garment. A still further object of this invention is to improve the life and wear of shorts by employing a panel of non-stretching material from the waistband to the crotch for support of the organs, which panel will outwear knitted material several times over.

To the accomplishment of the foregoing and related end, said invention then consists of the means hereinafter fully described and particularly pointed out in the claims, the following description sets forth in detail an improved pair of shorts in but one of various ways in which the principle of the invention may be used.

In said annexed drawings:

Fig. 1 is a perspective view of a pair of shorts; 55

2

Fig. 2 is a side view of a pair of shorts; and Fig. 3 is a plan view of the woven panel shown in Figs. 1 and 2.

My invention consists of a pair of shorts generally known as briefs or trunks, frequently made of elastic material or knitted in various combinations, to provide full support for the organs of the body. These shorts are held firmly in place by elastic members entirely or partially surrounding the waist or leg members. My invention consists in making a close-fitting pair of shorts having a front panel 10 of woven material of cotton, rayon, nylon or suitable material in one of several weaves. This woven material has the characteristic of only moderate stretch through long wear and washings. On the sides and back of the shorts is a panel of knitted material 11, connected to the woven material on a seam 12. Partially or completely surrounding the waist 13 is an elastic band 14 to provide holding support for the cloth and the parts of the body. The woven panel and the knitted panel join on the underside at about the center of the crotch at a line indicated at 15.

25 The woven panel 10 is made up of two separate pieces in the particular embodiment I have shown. One member 16 is of generally L shape shown preferably in Fig. 3 and consists of a lower portion truncated to an arcuate seam around the lower edge 17; by this I mean that it is tapered in the crotch and to a point not further than the approximate center thereof as is shown in Fig. 2. The other panel 18 is of generally rectangular form and is sewn to the member 16. An intermediate opening is shown at 19 as is customary in these garments. The larger panel section 16 is gathered at its sides 21 and 22 by an elastic member in each leg to provide a sack-like body shown in Fig. 2 at 23. Elastic members are not necessarily used in these legs but they may be.

30 This provides a pendant support from the waistband 13 for the organs and has the slight stretching qualities of the woven material which holds them loosely but properly in position. In garments using woven goods it is also possible and desirable to eliminate the elastic band across the front or stomach covering portion of the waistband, making for greater comfort and a smoother fit. In this line the woven panel is simply carried straight up to the top and attached to the ends of the elastic waistband at the edges of the knitted material.

45

50

The rear panel of the above garment is made of a knitted material having capacity to stretch in each of two directions, both the vertical and

the horizontal. This permits the garment to conform to the shape of the body and to be held firmly in place against the body without flapping while in use. The knitted material acts to keep the woven material in position, particularly along the gathered seams 21 and 22 on each leg opening. Thus it is seen that the knitted material 11 in the garment and the elastic members in the leg openings will retain the front panel or woven material in position but without stretching this panel either vertically or transversely. In operation the woven panel is supported from the waistbands and parts of the body in contact with it are held in position from the waist.

After considerable use the knitted portion of the garment may lose its resiliency and stretch permanently to some degree but the elastic members in the legs or their natural tightness if it is other material will still provide a permanent shape for the garment and the woven panel is substantially unchanged by this stretching operation. Before this invention a pair of briefs would stretch in the old form of knitted front panel, and after some time would not provide the support required. When this happened they were useless long before the material was worn out and the elastic bands had deteriorated.

Thus it is seen that my improved shorts provide the necessary support for a man and will not stretch greatly while in use or through washing and will perform their function for a much longer period of time. The invention may be embodied in other specific forms without departing from the spirit or essential characteristics thereof. The present embodiment, therefore, is to be considered in all respects as illustrative of the invention and not restrictive. The scope of the invention is indicated by the appended claims rather than by the foregoing description, and all changes which come within the meaning and range of equivalency of the claims are therefore intended to be embraced therein.

I therefore particularly point out and distinctly claim as my invention:

1. A pair of shorts for men, having a front panel of woven material and a rear panel of knitted material said woven panel being formed in the shape of a sack whereby the woven material supports the organs and is substantially unstretched by wearing, and the knitted material is capable of conforming to the shape of the wearer.

2. In a pair of trunks for men, the combination of a front panel of woven material and a rear panel of knitted material capable of stretch-

ing and conforming to the user, said front panel having a lower portion to the center of the crotch which portion is gathered at the sides to stretch in the shape of a sack.

3. In a pair of trunks for men, the combination of a front panel of woven material, a rear panel of knitted material and an elastic band on the top encompassing the garment; said woven panel tapered at the lower end to a point not further than the approximate center of the crotch, whereby said front panel will support the body and not stretch through wear though permitting the garment to conform to the shape of the user.

4. In a pair of trunks for men, the combination of a front panel of woven material, a rear panel of knitted material and an elastic supporting band on the top and both legs of the trunks, said front panel being tapered to the approximate center of the crotch, whereby the garment generally conforms to the shape of the user, but permits the organs to be pendants supported from the top elastic member and retained in position by the elastic members on the legs of the trunks.

5. In an undergarment, the combination of a fly front panel of woven material and a rear panel of knitted material contacting said front panel on a vertical line and an elastic supporting band attached to the top of said rear panel and also contacting said front panel on a vertical line, said undergarment having a crotch and leg openings with elastic members, the rear panel of knitted material and the elastic members in the leg openings retaining the front panel of woven material in position, the rear knitted panel closely conforming to the buttocks of the wearer by the stretching of the knitted fabric in order that the garment may be comfortable but still permit the woven fabric in the front panel to support the organs of the body pendants, retaining them in position by the resiliency in the knitted fabric attached to said woven material.
